WELL DRILLING APPARATUS

Esta I. Shoe and Forrest C. Landis,
Pleasant Hill, Ohio

Application April 26, 1933, Serial No. 668,084

17 Claims. (Cl. 255—11)

This invention relates to well drilling apparatus.

One of the principal objects of the invention is to provide a well drilling apparatus which is simple and economical in construction, easily and safely operated and controlled, highly efficient and effective in operation, and which affords increased drilling capacity as well as minimizing the likelihood of the drill or bit sticking in the bore of the well.

Another object of the invention is to provide a well drilling apparatus of the cable or percussion type with a drive for the rocker arm which reciprocates the cable, and which positively effects the upstroke of the bit and then releases the bit, together with means which then picks up the rocker arm to relieve weight of the rocker arm and related parts from the cable and provide cable slack to give a substantially free gravity fall of the bit on the cutting stroke.

Another object of the invention is to provide a well drilling apparatus of the character mentioned, with a resilient bumper which engages the rocker arm at the termination of the cutting stroke and before the start of the lifting stroke, the rocker arm being free to rebound from the resilient bumper, to thereby impart a sharp jerk upwardly on the cable and bit to minimize sticking of the bit.

Another object is to provide simple and effective mechanism for adjusting the stroke of the bit without interrupting the drilling operation, and without disturbing the drive.

Another object is to provide economical and effective mechanism for unwinding or rewinding the cable, which is driven from the usual drive for the drill, without reversing the direction of the drive, and which at the same time affords an easily controlled and readily adjustable rate of unwind or rewind of the cable.

Still another object of the invention is to provide a simple and effective control for the sand bucket reel and cable, with a manual control member for regulating the rate of unwind of the cable from the reel for the descent of the sand bucket, and for connecting the reel in driven engagement with the usual drive for the drill to lift the sand bucket from the well.

Other objects and advantages of the invention will be apparent from the following description when taken in connection with the accompanying drawings and appended claims.

In the drawings, in which like characters of reference designate like parts throughout the several views thereof,

Fig. 1 is a side elevational view of the drilling apparatus of the present invention, with a portion of the frame broken away to illustrate the construction of parts behind the frame;

Fig. 2 is a top plan view of the apparatus of Fig. 1, with the uprights which carry the pulleys for the drill cable and the sand bucket cable broken away and in section;

Fig. 3 is a side elevational view of the apparatus, looking from the opposite side from that of Fig. 1;

Fig. 4 is an enlarged top plan view of the rocker arm and cam drive;

Fig. 5 is a side elevational view of the clutch which interconnects the band wheel shaft with the cam discs, the view being taken from the left hand side of Fig. 4;

Fig. 6 is a detail side elevational view of the cam disc, showing the relative positions of the cam surfaces and cam roller at the beginning of the upstroke of the bit;

Fig. 7 is a view similar to Fig. 6, with the parts in the positions occupied at the termination of the upstroke of the bit and at the point of release for the gravity fall of the bit on the cutting stroke;

Fig. 8 is a view similar to Fig. 6, with the parts in the positions occupied just after the start of the cutting stroke of the bit, with the second cam surface engaging the cam roller to positively move the rocker arm to relieve weight of the rocker arm and related parts from the cable to provide a substantially free gravity fall of the bit;

Fig. 9 is a view similar to Fig. 6, also showing a portion of the rocker arm and spring bumper, with the parts in the positions occupied at substantially the completion of the cutting stroke of the bit;

Fig. 10 is a detail sectional view of the adjusting mechanism for the stroke of the bit, taken on the plane of the line 10—10 of Fig. 2, with the frame broken away;

Fig. 11 is a partial side elevational view, similar to Fig. 1, showing the friction drive for the cable feed in a different adjusted position;

Fig. 12 is a detail sectional view taken on the plane of the line 12—12 of Fig. 1, showing the eccentric mounting for the friction pulley shaft;

Fig. 13 is a view similar to Fig. 12, with the parts in a different position; and

Fig. 14 is an enlarged side elevational view similar to Fig. 1 of the drive and braking mechanism for the sand bucket reel, and control there-

for, with other parts omitted for the sake of clearness.

Referring to the drawings, which disclose a preferred embodiment of the invention, the frame 5 work or derrick, which may be portable or stationary, is composed of longitudinally extending timbers 10 at each side thereof, with cross braces 11. At the front or operator's end are uprights 12 secured by braces 13. The uprights 10 may be formed in several sections secured together at 14, and at their upper end pivotally support a drill cable pulley 15, over which passes the drill cable 16 which then extends downward and suspends the usual drilling tools including 15 a bit within the bore of the well. The apparatus shown is a drill of the cable or percussion type, in which drilling is accomplished by alternately moving the cable and bit up and down to give a series of impacts of the bit against the bottom 20 of the bore of the well (generally about 30 to 60 a. minute).

For reciprocating the cable, a rocker arm 18 is provided, which is pivotally mounted intermediate its ends in journals 19 carried by one of 25 the cross braces 11. The rocker arm is formed of two longitudinally extending beams which are rigidly connected together, and are spaced apart to receive pulleys 20 and 21 therebetween. Each pulley is journalled on a pin 22 fastened to the 30 spaced beams of the rocker arm. Cable 16 passes downwardly from pulley 15 to pulley 20, then under this pulley and under pulley 21, and thence up between the spaced beams and over a spool 23 carried at the opposite end of the rocker arm 18. Cable 16 then passes between guide rollers 24 and 25, and thence to a reel or bull wheel 26 on which the cable is wound, and from which it is gradually unwound as drilling proceeds and the well becomes deeper.

40 Power for oscillating rocker arm 18 is obtained by a belt drive (not shown) around band wheel 28, the belt extending around a pulley driven by a suitable steam or internal combustion engine or other suitable source of motive power (not shown). Band wheel 28 is pinned to a cross 45 shaft 29 rotatably mounted in bearings 30 fastened at the upper ends of posts 31 secured to frame members 10. Shaft 29 passes freely through a hollow sleeve 33. Fastened to sleeve 33 by bolts passing through flanges 36 at the 50 opposite ends of the sleeve 33, are cam discs 34 and 35. Cam disc 34 carries at its outer side an outwardly extending annular flange 38 forming a clutch ring or face, with which cooperates a conventional type of expanding friction clutch which 55 is keyed to rotate with shaft 29.

Any suitable type of clutch may be used. That shown has a collar 40 which is keyed to rotate with shaft 29 but is slideable axially along the 60 shaft. Collar 40 carries at diametrically opposed sides pivot lugs 41, to which are pivotally connected the adjacent ends of turnbuckle arms 42. The opposite ends of arms 42 are pivotally connected to lugs 43 carried at adjacent ends 65 of clutch shoes 44 which carry friction clutch pads 45. The opposite ends of clutch shoes 44 are pivotally connected to a ring 47 carried by spiders 48 connected to a central collar 49 which is pinned to shaft 29. Ring 47 is additionally supported by a brace bar 50 fastened to collar 49. A forked arm 51 rides within the groove 52 of collar 40, the arm being pivotally connected in a slotted end of lever 53 pivoted at 54 to cross frame 11. Pivotally connected to lever 70 53 is an arm 55, which in turn is pivoted to the

upper end of an upright shaft 56 journalled on post 31. The lower end of shaft 56 carries an arm 58 to which is pivotally connected one end 5 of a link 59. The opposite end of link 59 is pivoted to a clutch control lever 60 journalled at 61 on upright 12. Fig. 3 shows the parts in their respective positions with the clutch disconnected. By pulling down on control lever 60 (as shown in Fig. 3), this will swing arm 58 clockwise (as shown in Fig. 2), to rotate shaft 56 and thereby 10 swing arm 55 and lever 53 toward cam disc 34, which will slide collar 40 axially along shaft 29 toward cam disc 34. This will straighten out the turnbuckle arms 42 to cause engagement of friction pads 45 with clutch face 38 of disc 34, 15 to thereby connect cam discs 34 and 35 for rotation with shaft 29 when the latter is driven by a band wheel 28.

Each of the cam discs 34 and 35 carries on its inner side cam surfaces 64 and 65. As the cam 20 discs 34 and 35 are identical, except disposed oppositely so as to face each other, and except that the cam disc 34 carries the outer clutch surface 38 as previously described, only the cam surfaces 64 and 65 for clutch disc 34 are shown in the 25 drawings. It will be noted that two separate and discontinuous cam surfaces of generally spiral shape are provided on each disc. Bolted at 61 to the rocker arm 18 is a cross pin 68, which rotatably supports at its outer ends cam rollers 69 co-operating with the cam surfaces of discs 34 and 35 respectively. These cam rollers 69 extend into the sides of the cam discs, and each bears against or rolls along the exterior side of its respective cam surface 64 and the interior side of its respective cam surface 65. Cam discs with cam surfaces are arranged on each side of rocker arm 18 to prevent side strain or thrust.

Fig. 6 shows the relative positions of the parts at the beginning of the lifting or up-stroke of 40 the bit. At this time, the pulley end 20 of rocker arm 18 is at the extreme upper end of its stroke, so that the cable and bit are lowered to the bottom of the bore of the well. Rotation of the cam surface 64 depressing cam roller 69 downwardly to thereby swing pulley end 20 of rocker 18 downwardly to effect a lifting stroke of the bit. The cam drive provides a relatively powerful available lifting force with the use of a relatively small 50 powered engine or other motive force. In Fig. 7, the parts are shown in the positions occupied at the termination of the lifting stroke. At this time, the release end 70 of cam surface 64 is just about to move past cam roller 69 to thereby release the rocker arm and allow the cable and bit to fall by gravity on a cutting stroke. Immediately after the release of the rocker arm by cam surface 64, the second cam surface 65 picks up cam roller 69, as shown in Fig. 8, and positively 60 forces the pulley end 20 of rocker arm 18 upwardly. The design of cam surface 65, and the rate of rotation of the cam disc, are such that the pulley end of the rocker arm is forced upwardly at a rate faster than the initial part of 65 the gravity fall of the bit. This affords slack in cable 16, which provides a substantially free gravity fall of the bit on the cutting stroke. By this construction, force of the gravity fall of the bit and cable is not wastefully expended in overcoming inertia of the heavy rocker arm and parts carried thereby, or in imparting velocity of movement to the rocker arm on the cutting stroke. By removing the restraining and retarding influence 70 of the rocker arm from the cable on the cutting 75

stroke of the bit, substantially the full force produced by the free gravity fall of the bit is utilized in actual drilling, thereby obtaining increased drilling capacity and a more efficient drilling operation.

Mounted on cross piece 72 carried by side braces 73 bolted to frames 10 are strong leaf springs 74, as shown in Figs. 2 and 9. Two leaf springs are provided so as to overlie both beams of rocker arm 18, and are so positioned vertically as to be contacted by the pulley end 20 of the rocker arm at substantially the end of the cutting stroke of the bit. Fig. 9 shows the cam disc and related parts in this position of the cycle, and it is seen that at this time the release end 75 of cam surface 65 is approaching and is immediately adjacent cam roller 69. In the normal operation of the drill, with the rates of rotation of the band wheel shaft 29 within the range normally used and as mentioned above, the falling bit and cable tend to catch up with the upward movement of roller end 20 of the rocker arm at substantially the end of the cutting stroke, or at about the position indicated in Fig. 9. At this time, the rocker arm has already acquired substantial momentum of movement due to the positive drive from cam surface 65, so that relatively little force produced by the falling drill is expended on the rocker arm, as the cable becomes taut and imparts a resulting upward kick to the end of the rocker arm. This causes the rocker arm to move sharply into engagement with spring bumpers 74, because cam rollers 69 are free to move upwardly away from cam surfaces 65 under the force of the kick or pull imparted to the rocker arm by the bit and cable. The bit has now reached the bottom of the bore of the well and has performed a cutting stroke, and during this interval the release end 75 of cam surface 65 has moved beyond cam roller 69. The resiliency of spring bumpers 74 then produces a sharp rebound downwardly of pulley end 20 of the rocker arm to give a sharp upward jerk on the cable and bit. This is valuable in effecting the release of the bit should it tend to stick. It is found, particularly in drilling through certain marls and sticky clays, that a sharp tug or jerk of comparatively small magnitude will effect the release of a bit which tends to stick, where a steady pull of considerably greater magnitude, even sufficient to break the cable, will not do so. The present cam drive thus not only provides a substantially free gravity fall of the bit on the cutting stroke, but also gives a release kick or jerk to the bit at the end of the cutting stroke and before the lifting stroke has begun. Shortly after the release kick has been imparted to the cable and bit, the cam surface 64 again picks up cam roller 69 in the position of Fig. 6 for the lifting stroke of the bit, and the cycle is repeated. The present device also provides an effective and easily controlled mechanism for adjusting the length of stroke of the bit, and without interrupting the drilling operation. As previously described, cable 16 passes along the rocker arm 18 under pulleys 20 and 21 and over spool 23, and thence between guide rollers 24 and 25. The guide rollers are mounted at their opposite ends in adjustable frames 77. Each frame is pivotally connected at its upper end to a link 78, which in turn is pivoted to an inclined frame member 79. The lower end of each frame 77 is pivotally connected at 80 to a crank arm 81 keyed to a cross shaft 82 rotatably mounted in bearings 83 on side frames 10. Shaft 82 extends outwardly beyond one of the bearings 83 and has

fastened thereto a sector 84 carrying worm teeth which mesh with a worm 85 mounted on a shaft 86 which extends along the frame member 10 to the operator's end of the drill. At this end, shaft 86 is provided with a hand wheel 87. Rotation of the latter in one direction will cause rotation of shaft 82 to swing crank arms 81 clockwise and upwardly (as shown in Fig. 10) to raise vertically frame members 77 and rollers 24 and 25 carried thereby, until the run of cable 16 over spool 23 is above the normal range of movement of the spool during the oscillation of the rocker arm. The throw of the pulley end 20 of the rocker arm will then determine the extent of the stroke of the drill, and will provide the minimum stroke.

By rotating hand wheel 87 in the opposite direction, frames 77 and rollers 24 and 25 are lowered to bring the run of the cable 16 within the range of movement of spool 23 during oscillation of the rocker arm, so that the cable will be pulled upwardly in an inverted V-shape between pulley 21 and rollers 24 and 25 on each oscillation of the rocker arm, to thereby provide an increased stroke of the drill. The maximum stroke is that illustrated in Fig. 3, where the rollers 24 and 25 are adjusted downwardly until the run of the cable contacts with spool 23 when the spool is at the lower end of its oscillating stroke. With this mechanism, the cam drive and related parts remain undisturbed as to their operative assembly, while adjustment of the stroke of the drill is easily and quickly effected from the operator's end of the machine without interrupting the drilling operation.

As drilling proceeds and the well becomes deeper, cable 16 is gradually fed out or unwound from the reel or bull wheel 26. The present invention provides means for positively driving the reel and accurately controlling the rate of feed of the cable. As shown, the reel is mounted on a shaft 89 journaled in bearings 90 carried by the inclined frames 79, which latter are braced by straps 91 bolted to side frames 10, and by brace bars 92 fastened to uprights 93 carried at the ends of frame members 10. Shaft 89 is extended outwardly beyond one of the bearings 90 and has keyed thereto a worm wheel 95 meshing with a worm 96 mounted on a shaft 97 journaled in bearings 98 carried by a frame piece 99 bolted to the inclined frame 79 and brace 91. Shaft 97 is connected by a universal coupling 101 to a shaft 102, which is in turn connected by universal coupling 103 to a shaft 104 rotatably mounted in eccentric bushings 105 (Figs. 12 and 13), journaled for pivotal movement in sockets in the ends of upstanding posts 106.

Keyed to shaft 104 to rotate therewith and to slide axially therealong is a friction pulley 108 fastened to a collar 109. Pulley 108 is adapted to bear against the side of a friction wheel 110 pinned to band wheel shaft 29. Each of bushings 105 is formed with an ear 112 at the side of the adjacent arms 106. Ears 112 are pivotally connected to the upper ends of the links 114, which in turn are pivotally connected at their lower ends to crank arms 115 carried by a control shaft 116 journaled on side frame 10 and provided at the operator's end of the machine with a hand control lever 117. In the position of lever 117 shown in Fig. 1, bushings 105 and shaft 104 are in the positions illustrated in Fig. 13 in which shaft 104 is spaced away from friction wheel 110 so that friction pulley 108 is out of contact therewith, with the drive to the bull

wheel thereby disconnected. By turning lever 117 downwardly, arms 115 are rotated downwardly to thereby shift, through the connecting links 114, the bushings 105 into the position shown in Fig. 12, in which shaft 104 is shifted toward friction wheel 110, and the friction pulley 108 is thereby brought into driven engagement with friction wheel 110. Rotation of band wheel shaft 29 will thereby drive, through friction wheel 110 and pulley 108 and the interconnected shafting, the worm 96 to thus rotate worm wheel 95 and the bull wheel shaft.

In the position of the parts shown in Fig. 1, with friction pulley 108 on the left hand side of the vertical axis of the band wheel shaft 29, the bull wheel is rotated in a direction to feed out cable to allow the bit to penetrate deeper, as drilling proceeds. The rate of rotation of the bull wheel for a given R.P.M. of the band wheel shaft is controlled by varying the radial displacement of the position of contact of friction pulley 108 with friction wheel 110. This is accomplished by axially sliding friction pulley 108 along shaft 104. As shown, a forked lever riding in groove 120 of collar 109 is pivotally connected to the slotted end of a link 121, which is in turn pivoted to the end of an extensible and collapsible linkage. The latter comprises a link 122 which is pivoted intermediate its ends to a link 123, and at its end to a link 124; the latter is pivoted intermediate its ends to a link 125, and at its end to the side of post 106. Link 125 is also pivoted at one end to link 123, and at its opposite end to a connecting rod 127, which is in turn pivotally connected to a hand lever 128 journaled at 129 on side frame 10. A pawl 130 operated by finger control 131 mounted on lever 128, cooperates with a toothed sector 132 bolted to the frame, to hold lever 128 and friction pulley 108 in adjusted position. By releasing pawl 130 and rotating lever 128 clockwise (as shown in Fig. 1), the linkage is extended further to shift pulley 108 toward the left, to thereby increase the rate of feed or unwind of the drill cable from bull wheel 26 for a given rate of rotation of the band wheel shaft. By shifting lever 128 counter clockwise to the extreme end of its stroke, the linkage is collapsed to shift friction pulley 108 to the right into the position shown in Fig. 11, in which the pulley is on the right hand side of the vertical axis of band wheel shaft 29 and adjacent the periphery of friction wheel 110. This will drive the bull wheel at a comparatively rapid rate in the opposite direction to rewind the cable for removing the drilling tools from the bore of the well. The drive thus enables the bull wheel to be positively driven in opposite directions for unwinding and rewinding of the cable respectively, from a motive source having a unidirectional movement; and enables a common motive source to be used for the drilling operation and the feed of the cable, with a coordinated and instantly adjustable speed ratio therebetween.

The present device also provides a simplified and effective drive for the sand bucket cable, together with an easily operated control therefor. As shown particularly in Figs. 1 and 14, reel 136 for the sand bucket cable 140 is provided with a shaft 137 which is journaled in bearings 138 mounted on cross brace 11. The cable 140 passes upwardly from reel 136 around pulley 141 journaled adjacent the upper end of uprights 12 below the drill cable pulley 15, and thence downwardly to suspend a conventional type of sand bucket (not shown) within the bore of the well, when the drill and drill cable are removed therefrom. De-

scent of the sand bucket into the well is accomplished by gravity feed thereof, the rate of descent being controlled by a brake shoe 143 bearing against a friction wheel 144 mounted on shaft 137 beyond one end of reel 136. Shoe 143 is carried by a lever 146 pivoted at 147 to frame member 10. The opposite end of lever 146 is urged by spring 148, fastened at one end to the lever and at its other end to a portion of the frame, into a position of braking engagement with friction wheel 144. Lever 146 is connected by an adjustable link 149 with a manual control lever 150 pivoted at 151 to frame 10. Also connected to control lever 150 by adjustable link 152 is a bar 153 having a longitudinal slot 154 formed therein. Riding in slot 154 is a pin 155 to which are connected arms 156, the lower ends of which straddle the upper end of slotted bar 153, and the upper ends of which extend to opposite sides of a friction pulley 158 and are pivotally connected to shaft 159 of the friction pulley. Also pivotally connected to shaft 159 on opposite sides of pulley 158 are arms 160 which are interconnected at their outer ends by a pin 161 operating in slot 162 of a bar 163 fastened to upright 12. The arrangement of the pulley 158 and friction wheel 144 is such that they are in alignment with each other and with the friction wheel 110. The interconnection to the control lever 150 is so proportioned and adjusted that as the lever 150 is rocked downwardly from the position shown in Figs. 1 and 14, brake 143 is first released from the friction wheel 144, and further downward movement of lever 150 will then bring friction pulley 158 into position to transmit a drive from friction wheel 110 to friction wheel 144 to thereby rotate the sand bucket reel in a direction to wind up the cable 140 thereon and lift the sand bucket from the well.

The operation of the device is thought apparent from the foregoing description when taken in connection with the accompanying drawing. To begin a drilling operation, with the drive to the band wheel 28 connected to rotate shaft 29 and with clutch control lever 60 in the position shown in Fig. 3 in which the clutch drive to the cam discs is disconnected, the operator then guides the drilling tools attached to the end of cable 16 into the upper end of the bore of the well. The worm drive 95-96 to the bull wheel is such as to prevent the weight of the drilling tools from rotating the bull wheel, to thereby avoid the danger of the tools falling at runaway speed into the well. Hand lever 128 is then rocked clockwise, as shown in Fig. 1, to move friction pulley 108 toward the periphery of friction wheel 110 on the left hand side of the vertical axis of the band wheel shaft 29. Lever 117 is then rocked to throw the friction pulley into engagement with friction wheel 110, and a positive drive is thus obtained to feed out cable from bull wheel 26 to lower the drilling tools within the well. When the bit reaches the bottom of the well, lever 117 is then returned to position to disconnect the drive, and lever 128 is then rocked counterclockwise to move friction pulley 108 in toward the axis of friction wheel 110 to obtain a regulated feed of the cable for drilling. Clutch lever 60 is then actuated to engage the clutch and rotate cam discs 34 and 35 to oscillate rocker arm 18 in the manner previously described; and any necessary adjustment of the rate of feed of the cable as the drilling proceeds is effected by the control levers 117 and 128 in the manner previously described. Adjustment of the stroke 75

of the bit may also be effected by manipulation of the hand wheel 87 during the drilling operation.

When the bore of the well needs to be cleaned out by the sand bucket, clutch lever 60 is thrown to disconnect the cam drive to the rocker arm, levers 117 and 128 are manipulated to position the friction pulley 108 adjacent the periphery of friction wheel 110 at the right side of the vertical axis as shown in Fig. 11, which will then positively drive bull wheel 26 in the opposite direction to rewind the cable and raise the bit from the well. When this is accomplished, lever 117 is actuated to disconnect the friction drive to the bull wheel, the drilling tools and cable 16 are moved out of the way, the sand bucket and cable 140 are guided into position at the upper end of the bore of the well, and then are lowered at a controlled rate by moving lever 150 downwardly to release brake 143 from friction wheel 144 sufficiently to allow the sand bucket to descend, the lever 150 being released from time to time to allow spring 148 to apply the brake to check the descent. When the sand bucket has been lowered to the bottom of the well and has filled, lever 150 is then moved downwardly to entirely release brake 143 and to bring friction pulley 158 into position to transmit a drive from friction wheel 110 to friction wheel 144 to thereby rotate reel 136 in the opposite direction and positively wind up cable 140 to lift the sand bucket from the well. The cycle of operations is then repeated.

It is to be noted that the operation of the drilling apparatus is effected without stopping or reversing the direction of drive of the band wheel shaft 29, and without disconnecting the drilling tools or sand bucket from their respective cables. The entire operation is easily and conveniently controlled by manipulation of a comparatively few levers or manual control members positioned at the operator's end of the machine.

While the form of apparatus herein disclosed constitutes a preferred embodiment of the invention, it is to be understood that the invention is not limited to this precise form, and that changes may be made therein without departing from the scope of the invention as defined in the appended claims.

What is claimed is:

1. In a well drilling apparatus having a cable suspending a drilling bit within the bore of the well, a rocker arm cooperating with the cable for reciprocating the cable to provide impacts of the bit against the bottom of the bore of the well, a driving member, and a releasable driving connection between said driving member and said rocker arm for oscillating said rocker arm comprising means for moving the rocker arm to provide an upstroke to the cable and bit, said means having provisions for releasing its driving connection at the termination of the upstroke, and additional means for then positively moving the rocker arm in the opposite direction at a rate faster than the initial part of the resulting gravity fall of the bit and cable to thereby provide slack in the cable to give a substantially free gravity fall of the bit on the cutting stroke, and means providing rebound of the rocker arm at the end of its cutting stroke, said releasable connection enabling said rocker arm to move away from the driving connection on said rebound to impart a sharp upward jerk on the cable and bit.
2. In a well drilling apparatus having a cable suspending a drilling bit within the bore of the well, a rocker arm cooperating with the cable for reciprocating the cable to provide impacts of the bit against the bottom of the bore of the well, a driving member, and a driving connection between said driving member and said rocker arm for oscillating said rocker arm comprising means for moving the rocker arm to provide an upstroke to the cable and bit, said means having provisions for releasing its driving connection at the termination of the upstroke, and additional means for then positively moving the rocker arm in the opposite direction at a rate faster than the initial part of the resulting gravity fall of the bit and cable to thereby provide slack in the cable to give a substantially free gravity fall of the bit on the cutting stroke, said additional means having provisions for releasing its driving connection to the rocker arm should the bit and cable catch up with the rocker arm during the latter part of its movement in the opposite direction, so that the rocker arm is free to move away from the driving connection under the force of the jerk imparted to the rocker arm by the bit and cable.
3. In a well drilling apparatus having a cable suspending a drilling bit within the bore of the well, a rocker arm cooperating with the cable for reciprocating the cable to provide impacts of the bit against the bottom of the bore of the well, a driving member, and a cam driving connection between said driving member and said rocker arm for oscillating said rocker arm, comprising one cam member for positively moving the rocker arm in one direction to impart an upstroke to the bit, and a second cam member for positively moving the rocker arm in an opposite direction to remove weight of the rocker arm from the cable and provide a substantially free gravity fall of the bit on the cutting stroke thereof, said second cam member having a discontinuous surface to enable said rocker arm to move away from the said cam member in the event that the fall of the bit and consequent movement of the cable impart a jerk to the rocker arm.
4. In a well drilling apparatus having a cable suspending a drilling bit within the bore of the well, a rocker arm cooperating with the cable for reciprocating the cable to provide impacts of the bit against the bottom of the bore of the well, a band wheel, a rotary cam member driven by the band wheel, and a cam roller carried by the rocker arm cooperating with the cam member, said cam member having one discontinuous cam surface along which the roller moves on the upstroke of the bit, and a second discontinuous cam surface along which the roller moves on the cutting stroke of the bit to positively remove weight of the rocker arm from the cable and provide slack in the cable so as to insure a substantially free gravity fall of the bit, the said two cam surfaces being spaced apart a distance substantially greater than the diameter of said cam roller.
5. In a well drilling apparatus having a cable suspending a drilling bit within the bore of the well, a rocker arm having an end cooperating with the cable for reciprocating the cable to provide impacts of the bit against the bottom of the bore of the well, a band wheel, a rotary cam member driven by the band wheel, and a cam roller carried by the rocker arm cooperating with the cam member, said cam member having one

- cam surface along the outer side of which the roller moves on the upstroke of the bit, and a second cam surface along the inner side of which the roller moves on the cutting stroke of the bit, each cam surface being discontinuous and also open on one side thereof to provide for release of the driving connection to the rocker arm, the first mentioned cam surface positively moving the cable end of the rocker arm to give an upstroke to the bit, and the second mentioned cam surface positively moving the cable end of the rocker arm in the opposite direction to remove weight of the rocker arm from the cable and provide a substantially free gravity fall of the bit.
6. In a well drilling apparatus having a cable suspending a drilling bit within the bore of the well, a rocker arm cooperating with the cable for reciprocating the cable to provide impacts of the bit against the bottom of the bore of the well, a driving member, a driving connection between said driving member and said rocker arm for oscillating said rocker arm comprising means for moving the rocker arm provide an upstroke to the cable and bit, said means having provisions for releasing its driving connection at the termination of the upstroke, additional means for then positively moving the rocker arm in the opposite direction at a rate faster than the initial part of the resulting gravity fall of the bit and cable to thereby provide slack in the cable to give a substantially free gravity fall of the bit on the cutting stroke, said additional means having provisions for releasing its driving connection to the rocker arm when the bit and cable catch up with the rocker arm during the latter part of its movement in the opposite direction, so that the cable imparts a jerk to the rocker arm to thereby increase its momentum at the end of the cutting stroke of the bit, and a resilient bumper positioned to contact with the rocker arm at the end of the cutting stroke of the bit to thereby cause the rocker arm to rebound and impart a sharp jerk upwardly on the cable and bit just prior to the time the first mentioned means picks up the rocker arm for the upstroke of the bit.
7. In a well drilling apparatus having a cable suspending a drilling bit within the bore of the well, a rocker arm cooperating with the cable for reciprocating the cable to provide impacts of the bit against the bottom of the bore of the well, a driving member, and a cam driving connection between said driving member and said rocker arm for oscillating said rocker arm, comprising one cam member for positively moving the rocker arm in one direction to impart an upstroke to the bit, said cam member then releasing the rocker arm for a gravity fall of the bit on the cutting stroke, a second cam member for positively moving the rocker arm in an opposite direction to remove weight of the rocker arm from the cable and provide a substantially free gravity fall of the bit on the cutting stroke, said second cam member having provisions for releasing the rocker arm near the end of the cutting stroke of the bit, and a strong spring bumper positioned to contact with the rocker arm at the end of the cutting stroke of the bit to cause the rocker arm to rebound and impart a sharp jerk upwardly on the cable and bit just prior to the time the first mentioned cam member picks up the rocker arm for the upstroke of the bit.
8. In a well drilling apparatus having a cable suspending a drilling bit within the bore of the well, a rocker arm pivoted intermediate its ends and having one end cooperating with the cable for reciprocating the cable to provide impacts of the bit against the bottom of the bore of the well, said cable extending from said mentioned end of the rocker arm along the rocker arm and past the other end thereof, means beyond the other end of the rocker arm for receiving the cable, and means for adjusting the position of said means for varying the extent of contact of the said other end of the rocker arm with the adjacent run of the cable upon oscillation of the rocker arm to thereby vary the extent of stroke of the bit.
9. In a well drilling apparatus having a cable suspending a drill bit within the bore of the well, a rocker arm pivoted intermediate its ends for oscillating movement, the cable passing under one end of the rocker arm so as to be reciprocated by oscillation of the rocker arm to provide impacts of the bit against the bottom of the bore of the well, the cable extending from beneath said one end of the rocker arm along the rocker arm and above the opposite end of the arm, means beyond the opposite end of the rocker arm for receiving and guiding the cable comprising a pair of rollers through which the cable passes, and means for vertically adjusting said rollers to thereby vary the position of the run of the cable above the said opposite end of the rocker arm and consequently vary the extent of contact of the said opposite end of the arm with the cable to vary the stroke of the bit, said adjusting means providing ready adjustment of the stroke of the bit during drilling operation.
10. In a well drilling apparatus having a cable suspending a drilling bit within the bore of the well, a bull wheel having a reel on which said cable is wound and from which it is unwound as drilling proceeds, a cable guiding member receiving said cable as it passes from said reel, a rocker arm pivoted intermediate its ends, said cable passing from said guiding member above the adjacent end of said rocker arm and under the opposite end of said arm and thence to said bit, a band wheel, a driving connection from said band wheel to said rocker arm to oscillate said rocker arm to thereby reciprocate said cable to provide impacts of the bit against the bottom of the bore of the well, and means for vertically adjusting the position of said cable guiding member from an upper position in which the run of the cable over the adjacent end of said rocker arm is above the normal range of movement of said adjacent end of the arm so that the stroke of the bit is equal to the stroke of the rocker arm, to a lower position in which the run of the cable is in the path of movement of the said adjacent end of the rocker arm to thereby increase the stroke of the bit.
11. In a well drilling apparatus having a cable suspending a drilling bit within the bore of the well, a reel on which said cable is wound and from which it is unwound as drilling proceeds, a rocker arm cooperating with the cable to reciprocate the cable and provide impacts of the bit against the bottom of the bore of the well, a band wheel and shaft driven thereby, a driving connection from said band wheel and shaft to said rocker arm to oscillate said rocker arm and thereby reciprocate said cable and bit, a friction wheel driven from said band wheel shaft, a friction pulley engaging the surface of said friction wheel to be driven thereby, a driving connection from said friction pulley to said reel, and means for adjusting the contacting position of said pulley with respect to said friction wheel from one side of the axis of the said wheel to the other side.

thereof to provide a positive drive of said reel for both unwinding and rewinding of the cable for down and up feed respectively of said bit, said adjusting means also having provisions for adjusting the distance of the contacting position from the axis of said friction wheel to thereby vary the rate of unwinding and rewinding of said cable for a given speed of said band wheel shaft.

12. In a well drilling apparatus having a cable suspending a drilling bit within the bore of the well, a reel on which said cable is wound and from which it is unwound as drilling proceeds, a rocker arm cooperating with the cable to reciprocate the cable and provide impacts of the bit against the bottom of the bore of the well, a band wheel and shaft driven thereby, a driving connection from said band wheel and shaft to said rocker arm to oscillate said rocker arm and thereby reciprocate said cable and bit, a friction wheel driven from said band wheel shaft, a friction pulley engaging the surface of said friction wheel to be driven thereby, a shaft on which said friction pulley is mounted for rotation therewith and for axial movement therealong, a driving connection between said shaft and the said reel, a manual control member, and a collapsible and extensible linkage interconnecting said manual control member and said pulley for sliding said pulley along its shaft from one side of the axis of said friction wheel to the other side thereof to provide both unwinding and rewinding movements of said reel for down and up feed respectively of said bit, said manual control member and linkage also providing adjusting movement of the pulley radially from the axis of the friction wheel to thereby vary the rate of unwinding and rewinding of said cable for a given speed of said band wheel shaft.

13. In a well drilling apparatus having a cable suspending a drilling bit within the bore of the well, a reel on which said cable is wound and from which it is unwound as drilling proceeds, a rocker arm cooperating with the cable to reciprocate the cable and provide impacts of the bit against the bottom of the bore of the well, a band wheel and shaft driven thereby, a driving connection from said band wheel and shaft to said rocker arm to oscillate said rocker arm and thereby reciprocate said cable and bit, a friction wheel driven from said band wheel shaft, a friction pulley engaging the surface of said friction wheel to be driven thereby, a shaft on which said friction pulley is mounted for rotation therewith and for axial movement therealong, an eccentric mounting for said pulley shaft, means for varying the position of said eccentric mounting to thereby move the said pulley out of and into contact with said friction wheel at will, and means for varying the position of said pulley along its shaft to thereby vary the direction and rate of rotation of said pulley, and a driving connection from said friction pulley to said reel.

14. In a well drilling apparatus, a band wheel, a shaft driven thereby, a friction wheel driven from said band wheel shaft, a driving connection from said band wheel and shaft for operating a drill, a cable for suspending a sand bucket within the bore of the well, a reel for said sand bucket cable, a friction pulley for transmitting a drive from said friction wheel to said reel, a movable mounting for said friction pulley for connecting and disconnecting the said drive, a manual control lever, a brake connected to said manual control lever to be moved thereby, spring means for normally urg-

ing said lever into position to apply said brake to said reel, and an interconnection between said lever and said friction pulley arranged to move the friction pulley to break the driving connection between said friction wheel and said reel as said brake is applied to said reel, and to bring the friction pulley in position to establish a driving connection between said friction wheel and said reel after said brake has been removed from braking engagement with said reel.

15. In a well drilling apparatus having a cable suspending a drilling bit within the bore of the well, a rocker arm cooperating with the cable for reciprocating it to provide impacts of the bit against the bottom of the bore of the well, said rocker arm being arranged to contact with and flex said cable to provide an increased stroke of said bit for a given movement of said rocker arm, a band wheel and shaft driven thereby, a cam drive between said band wheel and shaft and the said rocker arm for oscillating the rocker arm, and means independent of the said cam drive for varying the stroke of said bit for a given movement of said rocker arm, said means comprising a member for varying the position of said cable with respect to said rocker arm to thereby vary the amount of flexing of said cable for the said given movement of said rocker arm, said last mentioned means providing adjustment of the stroke without discontinuing drilling operation.

16. In a well drilling apparatus having a cable suspending a drilling bit within the bore of a well, a pivoted rocker arm cooperating with said cable for reciprocating the latter to provide impacts of the bit against the bottom of the bore of the well, driving means for oscillating said rocker arm, a member carried by said rocker arm on one side of the pivot thereof around which said cable passes, the cable extending from said member longitudinally along said rocker arm to the other side of the pivot thereof, a second member carried by said rocker arm at the said other side of the pivot thereof adapted to contact therewith and flex said cable to provide an increased stroke of said bit for a given movement of said rocker arm, and means for varying the position of said cable with respect to said second member to thereby vary the amount of flexing of said cable for the said given movement of the rocker arm.

17. In a well drilling apparatus having a cable suspending a drilling bit within the bore of the well, a rocker arm comprising spaced parallel bars pivotally mounted intermediate their ends, a pulley mounted between said spaced bars at one side of the pivotal mounting thereof under which said cable passes toward the bit, the said cable extending rearwardly from the pulley along the said bars and upwardly through the space between them to the upper side thereof, driving means for oscillating said rocker arm, a member carried by the bars at the other side of the pivotal mounting thereof and adapted to contact with and flex the cable extending thereabove into an inverted V-shape to thereby increase the stroke of the bit for a given movement of the rocker arm, means beyond the said member for receiving the cable, and mechanism for vertically adjusting said receiving means to thereby vary the vertical positioning of said cable with respect to said member, and thus vary the extent of flexing of the cable for the said given stroke of the rocker arm.
